Patented June 24, 1975

235,583

COMBINED VEHICLE AUXILIARY FUEL TANK AND UTILITY COMPARTMENT

Alan C. Parry, Des Moines, Iowa, assignor to Mid-
America Body & Equipment Co., Inc.

Filed May 7, 1973, Ser. No. 358,006

Term of patent 14 years

Int. Cl. D3—02

U.S. Cl. D87—1 R

Fig. 1

Fig. 2

Fig. 3

Fig. 4

Fig. 5

FIG. 1 is a front, top and left side perspective view of a combined vehicle auxiliary fuel tank and utility compartment showing my new design;

FIG. 2 is a front elevational view;

FIG. 3 is a left side elevational view;

FIG. 4 is a right side elevational view; and

FIG. 5 is a top plan view.

I claim:

The ornamental design for a combined vehicle auxiliary fuel tank and utility compartment, substantially as shown.
